Primary Examiner — Rosemary K Tarcza*(74) Attorney, Agent, or Firm* — NSIP Law(57) **CLAIM**

The ornamental design for a battery for digital camera, as shown and described.

DESCRIPTION

FIG. 1 is a front perspective view of a battery for digital camera showing my new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is another front perspective view the battery for digital camera in which a digital camera in broken lines is provided to illustrate an example environment;

FIG. 9 is an enlarged view of the encircled portion as shown in FIG. 1; and,

FIG. 10 is an enlarged view of the encircled portion as shown in FIG. 1.

The broken lines illustrating portions of the battery for digital camera are for environmental purposes only and form no part of the claimed design.

The dot-dash broken lines encircling portions of the claimed design that are illustrated in enlargement form no part of the claimed design.
